UNITED STATES PATENT OFFICE.

GEORGE C. JENSEN, OF OAKLAND, CALIFORNIA.

SHIFTER-LOCK MECHANISM.

1,373,819.

Specification of Letters Patent. Patented Apr. 5, 1921.

Application filed June 25, 1919. Serial No. 306,698.

To all whom it may concern:

Be it known that I, GEORGE C. JENSEN, a citizen of the United States, residing at Oakland, in the county of Alameda and State of California, have invented certain new and useful Improvements in Shifter-Lock Mechanism, of which the following is a specification.

The present invention relates to an improved and simplified form of gear shifter retainer, lock, and interlock, and has for its principal objects to provide a construction wherein the members coöperating with the shifters are yieldably held apart in engagement with the shifters by a spring held device, and wherein a locking bolt is provided for positioning to preclude the movement of said members toward each other, thereby locking the same in engagement with the shifters. To provide a construction wherein the members coöperating with the shifters are capable of being cheaply manufactured, and also wherein the spring held retaining member is also capable of being cheaply manufactured, whereby the construction is materially simplified and is capable of being manufactured and assembled at little cost.

With the above mentioned and other objects in view, the invention consists in the novel construction and combination of parts hereinafter described, illustrated in the accompanying drawings and pointed out in the claims hereto appended; it being understood that various changes in the form, proportion, size, and minor details of construction within the scope of the claims may be resorted to without departing from the spirit or sacrificing any of the advantages of the invention.

To more fully comprehend the invention, reference is directed to the accompanying drawings, wherein—

Figure 1 is a view in broken side elevation of the preferred embodiment of my invention.

Fig. 2 is a sectional view taken on line 2—2 of Fig. 1, viewed in the direction of the arrows.

Fig. 3 is a transverse sectional view taken on line 3—3 of Fig. 2.

Fig. 4 is a view similar to Fig. 1, but disclosing a slightly modified form of construction.

Fig. 5 is a sectional view illustrating the parts in elevation as disclosed by a vertical section through the plunger.

Fig. 6 is a sectional view taken on line 6—6 of Fig. 5.

Referring to Figs. 1, 2 and 3, the numeral 1 designates a conventional form of gear box consisting of the base 2 and cover 3. The box is provided with the usual aligned openings 4 arranged in spaced relation and within which operate the longitudinally movable parallel spaced gear shifters 5 selectively operated by any suitable mechanism, such as a lever 6. The gear box is provided with a bore 7 connecting said openings 4, and said bore 7 is intersected by a bore 8 disposed preferably at right angles thereto, and extending vertically, the upper end of said bore being reduced, as at 9, providing a shoulder 10. The bore 8 extends both into the base 2 and cover 3, and in the upper end of said bore is mounted for longitudinal movement a locking bolt 11 preferably formed with a reduced lower end 12, the upper end of said bolt adapted for projecting through the reduced opening 9 of the bore 8.

A shoulder 13 is formed between the upper portion and reduced lower end 12 of the bolt 11, and when the bolt is in its uppermost position said shoulder contacts with the shoulder 10 and precludes further upward movement of said bolt. The bolt when depressed is adapted to be automatically locked in such position by any form of spring pressed, key released locking device, conventionally illustrated by the reference numeral 14.

Positioned at the lower end of the bore 8, formed within the cover 3, is a suitable retaining plate 15, formed with an opening 95 through which the end 12 of said bolt operates, and positioned between said plate and the undersurface of the shoulder 13 is a coiled spring 16 for normally retaining the bolt in raised or retracted position.

The shifters 5 are formed in adjacent faces with the usual stops 17 with which are

adapted to engage the outer tapered ends of the members 19 positioned within said bore 7, one to coöperate with the stops of the respective shifters, and said members being 5 of a length equal to the distance between said shifters 5 plus the depth of one of the stops 17 so that on the movement of one of said stops 17 from its associated member said member will contact at its inner end 10 with the other member and maintain said other member in engagement with its associated stop 17, providing an interlock between said shifters. The shifters are also provided with the usual speed stops 20, and on 15 the movement of one of said shifters to speed position, one of said stops 20 will coöperate with the end of the member 19 associated with the moved shifter, at which time the inner ends of said members will be in slight 20 spaced relation.

To normally separate said members to retain said shifters in their adjusted position, a ball 21 is positioned in the bore 8 below said members 19, the same being upwardly pressed by a coiled spring 22 within the upper end of which said ball is seated, said spring maintaining the ball in contact with the beveled surfaces 23, at adjacent ends of the members 19.

30 The ball 21 being held by the upper end of the coiled spring 22 is capable of movement laterally of the bore 8 and longitudinally of the bore, whereby on the inward movement of one of said members 19 35 the surface of the ball will ride on its beveled surface, and also ride on the beveled surface of the other member 19, insuring that said other member will be maintained in contact with its associated stop.

40 On the depression of the bolt 11, when the shifters are in a position, as in Fig. 3, the lower reduced end 12 thereof is of a size to snugly fit between the adjacent ends of the members 19 and preclude inward movement 45 thereof on the operation of said shifters, whereby said shifters are locked from movement.

In the present construction it will be observed that the bore 8 extends both above 50 and below the bore 7 and that the member for yieldably separating the members 19 to retain the shifters 5 in their adjusted position is in the form of a ball upwardly forced by a coiled spring engaging the lower 55 end of the bore 8.

It will also be apparent that the locking bolt is of simple construction and is normally held upwardly or in released position by a coiled spring 16, said bolt being 60 automatically locked in depressed position by a key released lock mechanism of any conventional type.

The construction illustrated in Figs. 4, 5 and 6 includes the same arrangement of 65 elements as in Figs. 1, 2 and 3, with the

exception that the retaining means or the means for yieldably separating the members 19 is of a different form than that illustrated in Figs. 1, 2 and 3.

In the modified construction, the bore 8 70 terminates at its intersection with the bore 7, and the members 19 are turned to position the beveled faces 23 thereof upwardly. In this modified construction the retaining means is in the form of a plunger 24 vertically movable within the lower end of the bore 8 and formed with a conical lower end 25, the plunger being provided with a vertical bore 26 through which extends the lower end 12 of the bolt 11, said plunger and bolt 80 being capable of movement within the bore 8 independently of each other. A single spring 27 is employed in the modified construction for normally maintaining the bolt 11 in raised or retracted position and for yieldably maintaining the plunger in engagement with the beveled surfaces 23 of the members 19, said spring being coiled about the reduced end 12 of the bolt 11 and positioned between the underside of the flange 90 13 and the upper surfaces of the plunger 24.

Having thus described my invention, what I claim as new and desire to protect by Letters Patent is:—

1. In combination with a pair of gear 95 shifters provided with stops, a pair of movable members positioned therebetween for engaging said shifters, a locking bolt movable between said members to maintain the same in locked engagement with said 100 shifters, and a spring held device coöperating with the adjacent ends of said members and movable independently of the bolt for yieldably maintaining the said members in coöperative relation with said shifters to retain said shifters in their adjusted 105 position.

2. In combination with a pair of gear shifters provided with stops, a pair of movable members positioned therebetween for 110 engaging said shifters, said members having beveled adjacent ends, a locking bolt movable between said members to maintain the same in locked engagement with said shifters, and a spring held device coöperating with the adjacent beveled ends of said members and movable independently of the bolt for yieldably separating the members to maintain the same in coöperation with said shifters to retain said shifters in 115 120 their adjusted position.

3. In combination with a gear shifter provided with a plurality of stops, a member movable laterally to and from said shifter for coöperation with the stops 125 thereof, said member provided with a beveled surface, a locking bolt capable of positioning to engage the said member when received in said stops to preclude disengagement of the member from said stop on 130

- the movement of the shifter device, and a separate spring held device coöoperating with the beveled surface of said member and movable independently of the bolt 5 for normally and yieldably maintaining the outer end of said member in engagement with said shifter and normally seated within one of said stops to maintain said shifter in its adjusted position.
- 10 4. In combination with a pair of gear shifters provided on adjacent surfaces with stops, a pair of movable members positioned therebetween for engaging the shifters, said members formed on their adjacent inner ends with beveled surfaces, a spring disposed angularly to the inner ends of said members, a device yieldably held by said spring in engagement with the beveled surfaces of said members for normally separating said members to yieldably retain the outer ends thereof in coöperation with said shifters to retain said shifters in their adjusted position, and a locking member movable independently of said device at all 20 times and capable of operation to lock through said members said shifters from movement.
5. In combination with a pair of gear shifters provided with stops, a walled opening connecting said gear shifters and intersected by a second walled opening arranged at an angle to said first walled opening, said second walled opening being open at its upper end, a pair of movable members positioned within said first walled opening and adapted one for coöoperating with the stops of each of said shifters, said members provided on their adjacent inner ends with a beveled surface, a spring held device within 30 said second opening for yieldably engaging said beveled surfaces to normally separate said members to maintain their outer ends in yieldable engagement with the stops of said shifters, and a locking bolt movable independently of said spring held device and within said second opening and longitudinally movable to position the inner end thereof between said members to preclude movement of said members toward each 40 other.
6. In combination with a pair of gear shifters provided with stops on their adjacent faces, a walled opening connecting said shifters, a second walled opening intersecting said first walled opening and extending therethrough, said second walled opening being open at one end, a pair of movable members positioned between said first walled opening and one coöoperating 50 with each of said shifters, said members provided on their adjacent inner ends with beveled surfaces, a coiled spring in the said second opening, a reciprocating member associated with one end thereof and maintained thereby in engagement with the bevel- 60
- eled surfaces of said members to normally separate the same and maintain the outer ends thereof in yieldable engagement with said shifters, a locking bolt longitudinally movable independently of said spring held device and positioned within the upper end of said second opening with its upper end projecting through the upper open end of said second opening, said bolt adapted for depression to position the lower end thereof 70 between the inner ends of said members to preclude movement of the same toward each other, a spring for normally retaining said bolt in its raised position, and means for locking said bolt in its depressed position. 75
7. In combination with a pair of gear shifters provided on adjacent surfaces with a stop, a pair of movable members positioned therebetween for coöperating at their opposite ends with said shifters, said members formed on their adjacent inner ends with beveled surfaces, a spring disposed angularly to the inner ends of said members, a separating device having a surface fashioned to coöperate with the beveled surfaces 80 of said members and disposed between the beveled surfaces of said members and said spring for normally separating said members to yieldably retain the outer ends thereof in coöperation with said shifters to retain said shifters in their adjusted position, and a locking bolt capable of reciprocating movement to engage said members to lock the same in engagement with said stop, independently of said separating device. 85
8. In combination with a pair of gear shifters provided on adjacent surfaces with a stop, a pair of movable members positioned therebetween for coöperating at their opposite ends with said shifters, said members formed on their adjacent inner ends with beveled surfaces, a spring disposed angularly to the inner ends of said members, a separating device yieldably held by said spring in engagement with said beveled surfaces of said members for normally separating said members to yieldably retain the outer ends thereof in coöperation with said shifters to retain said shifters in their adjusted position, and means operatable independently of said separator and movable at all times independently of said device for locking said members in engagement with said stops. 90
9. In combination with a pair of gear shifters provided on adjacent surfaces with a stop, a pair of movable members positioned therebetween for coöperating at their opposite ends with said shifters, said members formed on their adjacent inner ends with beveled surfaces, a spring disposed angularly to the inner ends of said members, a spreader having a surface fashioned to coöperate with the beveled surfaces of said members and disposed between the beveled 100
- 105
- 110
- 115
- 120
- 125
- 130

surfaces of said members and said spring for normally separating said members to yieldably retain the outer ends thereof in co-operation with said shifters to retain said shifters in their adjusted position, and a locking bolt movable at all times independently of said spreader for positioning between the adjacent ends of said members to preclude inward movement of said mem-

bers to lock said shifters in their adjusted 10 position.

In testimony whereof I have signed my name to this specification in the presence of a subscribing witness.

GEORGE C. JENSEN
